UNITED STATES PATENT OFFICE.

CHARLES G. FASOLDT, OF GRAND RAPIDS, MICHIGAN.

SUSPENDER-BUCKLE.

1,182,156.

Specification of Letters Patent.

Patented May 9, 1916.

Application filed November 2, 1914. Serial No. 869,968.

To all whom it may concern:

Be it known that I, CHARLES G. FASOLDT, a citizen of the United States, residing at Grand Rapids, in the county of Kent and 5 State of Michigan, have invented certain new and useful Improvements in Suspender-Buckles, of which the following is a specification.

My invention relates to improvements in 10 garment buckles, and its object is to provide a garment buckle, as for use upon suspenders, with which the buckle itself will provide for contracting and expanding the suspender longitudinally, auxiliary to the 15 usual elasticity of suspenders, but more particularly for use upon overall suspenders where no outside garment is worn over them. I attain this object by the construction and arrangement of parts shown in the accompanying drawing, in which:

Figure 1 is a plan of the buckle complete. Fig. 2 shows the suspender or strap in position in the buckle. Fig. 3 is an edge view of the same.

Similar numerals refer to similar parts throughout the several views.

In the accompanying drawing 1 represents the body of the buckle having an integral cross bar 13, and inwardly projecting arms 19 upon which the buckle points 2 are formed.

3 is a cross bar that is firmly secured to, and extends across the body 1 and is designed, in Figs. 1, 2 and 3 to form a pivotal support for the adjustable arm 7 and, also, for one fold of the suspender to pass around. The arms 4 are pivotally connected with the arms 19, as shown in Fig. 1, and have a cross bar 5 connecting them and forming 40 a support for the suspender or strap 15 and for the points of the prongs 2. The arms 4 have an integral cross bar 6 that, with the cross bar 5, forms a loop for the passage of the end 14 of the suspender or strap 15, 45 14. The adjustable arm 7, consists of the side pieces 7 and the integral cross bar 7'. The arms 7 are pivotally connected with the cross bar 3, as at 8, and has an actuating spring 9 that is made in two in-

tegral sections, one on each side of the offset 10 back of which the connecting link 21 passes, while the bodies of the spring are coiled around the cross bar 3 with the ends connected with the arms 7, 7 in such a manner that the arm 7, 7, 7' will be held firmly 55 against the body 1 and arms 19 of the buckle, as shown in Figs. 1, 2 and 3.

When threading the buckle the suspender is passed back of the cross bar 13, in front of 3 and over 7', thence back, down and around 18, up in front of the arms 19, with the points 2 passed through it, and thence through the loop between 5 and 6, as shown in the three first figures in the drawing. It will be readily understood that with this 60 construction, and with the end 15 of the suspender, strap or belt properly supported, as over the shoulder of the wearer, any strain or pull on the end 14 of the same will tend to draw the arm 7, 7' downward and outward, as indicated by its dotted lines in Fig. 3, against the tension of the spring 9 which will constantly draw upon, and take up any slack that may be allowed or caused at the end 14 thus insuring an equal strain 65 on the suspender regardless of the position of the wearer, whether stooping, standing erect or leaning to one side or the other from the perpendicular.

What I claim as new, and desire to secure 70 by Letters Patent of the United States, is:

1. In combination with the body, of a suspender buckle; a cross bar permanently secured across the body near the longitudinal center thereof, an adjustable cross bar having arms at right angles therewith and pivotally connected with the permanent cross bar, and a spring coiled around the permanent cross bar and anchored thereto near the longitudinal center thereof, and the ends of 85 said spring connected with the arms of the adjustable cross bar to hold said bar normally against the body.

2. In combination with the body, of a suspender buckle; a cross bar permanently located across the body near its longitudinal center, an adjustable cross bar having arms at right angles therewith, the ends of said 90

arms pivotally connected with the permanent cross bar, a spring wire anchored near the center of the permanent cross bar and then coiled around said bar to each end and
5 the ends connected with the arms of the adjustable cross bar forming a spring to hold said cross bar normally against the body and to impart elasticity to the suspender

by the action of the adjustable cross bar and said spring.

Signed at Grand Rapids, Michigan, Oc-
tober 29, 1914.

CHARLES G. FASOLDT.
